Patented May 5, 1959

185,102

LAWN SPRINKLER

Edwin W. Smith, Climax, Mich., assignor to Atlas Press Company, Kalamazoo, Mich., a corporation of Michigan

Application August 12, 1957, Serial No. 47,333

Term of patent 14 years

(Cl. D91—1)

Figure 1 is a perspective view of a lawn sprinkler embodying the new design.

Figure 2 is a side elevational view thereof.

Figure 3 is a top plan view thereof.

Figure 4 is a rear elevational view thereof.

Figure 5 is a front elevational view thereof.

The characteristic features of the lawn sprinkler reside in the portions shown in solid lines.

I claim:

The ornamental design for a lawn sprinkler, as shown and described.
